UNITED STATES PATENT OFFICE.

OTTO PETERMANN, OF GROTON, NEW YORK, ASSIGNOR TO CORONA TYPEWRITER COMPANY, INCORPORATED, A CORPORATION OF NEW YORK.

ESCAPEMENT MECHANISM FOR TYPE-WRITING MACHINES.

1,140,848.

Specification of Letters Patent. Patented May 25, 1915.

Application filed May 1, 1911. Serial No. 624,818.

To all whom it may concern:

Be it known that I, OTTO PETERMANN, a citizen of the Republic of Switzerland, and a resident of Groton, county of Tompkins, and State of New York, have invented certain new and useful Improvements in Escapement Mechanisms for Type-Writing Machines, of which the following is a full, clear, and exact description.

10 This invention relates more particularly to the escapement mechanism of visible or front-strike typewriters, and is especially applicable to that class of typewriting machines in which the carriage and platen together with a part of the escapement mechanism is foldable forward over the key-levers or type-bars, or otherwise shifted into compact relation to another part of the machine to adapt the machine for transportation or

20 other purposes.

One of the main objects of the invention is to provide simple and efficient mechanism in which a rotary escapement wheel forms a part thereof and in which the coöperating parts are so connected to the key-levers that the said mechanism will be operated on the last quarter of the printing movement of the type-bars to release the loose dog from engagement with the escapement wheel and 25 to cause the fixed dog to engage therewith, and on the return movement of any type-bar in the opposite direction, and in a comparatively small part of its movement, the carriage is permitted to move a short distance for letter spacing, and owing to the short distance of travel of the type-bar necessary to permit the escapement to operate properly practically all liability to piling letters one upon another is thereby avoided.

40 Another object of the invention is to provide simple and efficient feed and escapement mechanism in which a part thereof is separable from another part and so adapted that the carriage, platen and part of the mechanism may be folded or shifted into compact relation to another part of the machine.

45 A further object of the invention is to provide a simple and efficient escapement mechanism which may be readily made and assembled.

50 A still further object of the invention is to provide simple and efficient mechanism for releasing the dogs from engagement with their coöperating element.

With these and other objects in view, the invention will be hereinafter more particularly described with reference to the accompanying drawings, which form a part of this specification, and will then be pointed out in the claims at the end of the description.

In the drawings, Figure 1 is a longitudinal section, partly in elevation, of one form of machine embodying my invention, showing the parts in their normal position. Fig. 2 is a rear elevation of the machine showing a part of the machine frame broken away and in section to better illustrate some of the working parts. Fig. 3 is a sectional plan view taken directly under the carriage bed, showing a part of the feed or escapement mechanism on an enlarged scale. Fig. 4 is a vertical section through the carriage bed, showing the mechanism of Fig. 3 in elevation and looking from the front of the machine; and Fig. 5 is a sectional plan view of the mechanism shown in Figs. 3 and 4 with the parts inverted, as for example, when the carriage is in a folded position.

While I show and describe the invention as used in a typewriting machine in which the carriage and platen are foldable forward over the keyboard, it is to be understood that the invention may be used in connection with typewriting machines of various constructions.

The frame 10 may be of any suitable construction and may have a transversely extending bar 11 at the front thereof to connect the sides of the frame together. A number of key-levers 12 are suitably mounted between the sides of the frame and are arranged in banks or groups 13, 14 and 15 in the usual way. Each key-lever is guided at the front portion thereof by a comb plate 15^a and at its rear by a comb plate 16, and extending below the member 11 is a vertical plate 17 to which is attached one end of springs 18, the other end of said springs being secured to the key-levers at the rear of the comb plate 16, there being a spring for each key-lever tending normally to force the inner end thereof downward and the outer end upward. The key-levers each have a downwardly extending part 19 and an ear or angular portion 20 which is connected to a link 21, one end of which link is connected to one of the type-bars 22. The type-bars 22, one for each key-lever, are

2
pivoted at 23 to hangers 24, which latter are secured to the rear bar or plate 25 of the machine frame, and each type-bar at the forward end is provided with a type-head 26 on which may be arranged a plurality of characters, indicating the upper case, lower case and figures or otherwise as desired.

The type-bars are moved to printing position through the operation of the key-levers and are adapted to print on the work sheet on the platen 27 in the usual way. The platen 27 is mounted upon a carriage 28 and this carriage is adapted to move 15 along the carriage bed 29, on which bed the carriage is supported in any preferred way. The carriage is moved along its bed by a suitable propelling device, as a spring actuated drum 30. As shown, this drum is 20 mounted under the carriage bed and has a flexible connection, as 31, which passes around a pulley or idler 32 secured to a bracket on the rear of the carriage bed and the forward end of said flexible connection 25 is attached to a bracket 33, Fig. 2, so that the spring actuated drum will tend to force the carriage along the bed as is usual in typewriting machines. The carriage bed is held to a support 34 and this support 30 comprises two parts, on the foldable part of which the carriage bed is mounted, and this part is pivoted at 35 to the other part or normally fixed member of the support so that the carriage, platen and propelling 35 mechanism may be folded forward so that the platen may rest upon the frame 10 to adapt the machine to be made compact for transportation or similar purposes. The support 34 with its carriage is shiftable 40 vertically by the vertically movable posts or slides 36 located at each rear corner of the machine, and these posts are connected together at their lower ends by a transversely extending rod 37, the said rod being connected to a platen shift lever 38. The lever 38 is pivoted to the transverse rod and ordinarily there are two shift levers, one for the upper case and one for the figures, though only one shift lever is shown, as 45 the extent or character of the shift is not important so far as this invention is concerned and for that reason is not further illustrated. The parts thus described may be of the usual or of any preferred construction.

A rack 40 is secured to the carriage base 41 under the same, and over the carriage bed 29 and adapted to engage the teeth of said rack is a pinion 42. This pinion 42 is 50 secured to a vertically arranged shaft 43 which is held to rotate in the frame 44. This frame 44 comprises a base plate 45 which is secured to the carriage bed 29 by means of screws 46, and held to said frame 55 member 45 is a second member 47. This

member 47 is provided with feet 48 which are secured by screws 49 to the base member 45 and said member is provided with vertical portions or bars 50 and 51 which are connected by a horizontally arranged bearing portion 52, the latter serving to support the lower end of the shaft 43. An escapement wheel 53 is held to the shaft 43 under the frame member 45. This wheel has teeth adapted to be engaged by a fixed dog or tooth 54, and a loose dog 55. The fixed dog forms a part of a lever 56 and this lever 56 is pivoted by a screw 57 to a lug 58 projecting outward from the escapement frame member 45. The lever 56 has an arm 59 on which is an angular or flange portion 60. A screw 61 passes through a threaded opening in the flange portion 60 and is held against movement after being adjusted by a lock nut 62, the end of said screw being adapted to engage the edge of the vertical bar portion 51 of the frame member 44 to serve as a stop and to limit the movement of said lever in one direction. A spring 63 is provided which has one end connected to the lever 56 or to a screw 64 thereon, and its other end held to the threaded end of a screw 65. The screw 65 is adjustable in a lug 65^a on the escapement frame 44, and is held in its adjusted position by a lock nut, 95 and said screw by having its end threaded into the end of the spring 63 will serve when rotated to vary the tension of said spring, the said spring tending normally to force the lever 56 in a direction to disengage the fixed dog or tooth 54 from the teeth of the wheel 53.

A lever 66 is pivoted at 67 to the lever 56 and this lever has an arm 67^a to which the loose dog 55 is pivoted. A screw 68 serves 105 as a pivot for the loose dog 55 and this dog has one end formed as a tooth which is adapted to engage the teeth of the escapement wheel 53. The arm 69 of the loose dog extends on the opposite side of the 110 pivot screw 68 to which one end of a spring 70 is attached, the other end of said spring being attached to a screw 71 carried by the lever 66, the tendency of the spring being to force forward the tooth of the dog 55 115 when released from engagement with the teeth of the ratchet wheel when the lever 56 is operated as will be presently described to permit the carriage to move for letter spacing. The lever 56 may be termed the fixed-dog lever and the lever 66 the loose-dog lever, and this latter lever while movable with the lever 56 also has a limited relative movement on its pivot 67 independent of the said lever 56. A spring 73 has one end attached to the screw 71 and the other end attached to a screw 74 carried by the fixed-dog lever 56 and which tends to hold the two levers in their normal position and to cause the end 75 of the loose-dog lever 66 130

to engage a stop 76 carried by the fixed dog lever 56. The stop 76 is in the form of an adjustable screw and passes through a threaded opening in a lug or portion 77 projecting downward from the fixed-dog lever, and said screw is held in an adjusted position by means of a lock nut 78. The lug 77 is extended to have one end located adjacent to the dog 55 so that when the latter is released by the movement of the lever 66 the spring 70 will force the dog against the lug which serves as a stop for said dog. The arm 67 on the lever 66 has an angular portion 79, and this angular portion has a threaded opening through which passes a screw 80 serving as a stop to limit the movement of the loose dog 55 in one direction, the said stop 79 being held in its adjusted position by a lock nut 81.

20 It will be seen that if the lever 56 is moved on its pivot 57, the lever 66 will also be moved therewith and this will cause the fixed dog 54 to engage one of the teeth of the ratchet wheel 53 and will cause the loose dog 55 to be disengaged therefrom owing to the action of the movement of said levers. As soon as the lever 56 is moved in the opposite direction the lever 66 will also be moved therewith to carry the dog 55 again in the path of the teeth of the wheel 53 which will permit the carriage through its propelling mechanism to move a distance of one tooth and until the arm 69 of the loose dog 55 engages the stop or screw 80. It will also be seen that if the fixed dog is out of engagement with the teeth of the ratchet wheel and the lever 66 is moved on its pivot 67, as will be presently described, both dogs will then be free of the ratchet wheel 53 and 40 the carriage may then be moved forward independent of the escapement mechanism through the propelling mechanism, it being understood that the carriage can at all times be moved backward or against the letter spacing movement in the usual way.

To actuate the lever 56 for letter spacing of the carriage by means of the key-levers various means may be employed. As shown, a rocking frame 82 is held to rock on the transverse rod 37 and is vertically movable therewith when the support 34 for the carriage and platen is elevated through the platen shift lever 38. This frame is substantially U-shaped and is preferably made in a single piece and comprises a transversely and horizontally extending bar 83 and the vertical arms or parts 84. The vertical parts 84 are slotted at 85 and passing through said slots is a transverse rod 86 each end of which rod 86 is held to the upper end of a bell-crank lever 87. The bell-crank levers 87 are each pivoted to a screw 88 which is held in a lug 89 located at a point adjacent to each of the slides or posts 36, said lugs being formed as a part

of the machine frame 10. Each bell-crank lever is pivotally held at 90 to arms 91 which are formed as a part of the universal bar 92, the said universal bar extending transversely of the machine and lying over the ears 92^a of the key-levers 12 as well as the levers of the spacing means. The universal bar may be formed integral with the arms 91 and may be formed as a straight or angular bar as desired. The bar with the arms 91 form a substantially U-shaped frame and has its bar or bar portion 92 guided in the slotted end 93 of a bracket 94 which is secured to the rear frame bar or side 25. A spring 95 is attached at one end to the transverse rod 86 and the other end of said spring is held to a plate 96. This plate may have a plurality of apertures 97 to which one end of the spring 95 may be attached for varying the tension of said spring, though, instead of the spring being attached to the plate 96 it may be extended over and attached to any other part of the machine.

The purpose of constructing the universal bar and actuating mechanism in the manner shown is to provide a mechanism which will insure a uniform motion no matter which key-lever is operated. This is effected by the rod 86 which extends through the slot 85 of the rocking frame and cooperates with the transverse rod 37 to keep the parts in proper alinement both at the lower portion and at the upper portion thereof so that there is less tendency for any of the parts to cant or shift as might occur if such means were not provided.

It will be seen that when any one of the key-levers is depressed the ear or end 92^a will engage the universal bar and this will cause the arms 91 to rock the bell-crank levers 87 on their pivots 88, and this through the rod 86 will move the rocking frame 84 on the shaft or rod 37. The rocking frame 84 is provided with a tappet 98 on the upper transverse bar 83 thereof and this tappet at the outward movement of the rocking frame will engage the end 99 of the escapement lever 56 so as to cause the fixed dog to engage one of the teeth of the ratchet wheel 53 and thus disengage the loose dog 55 therefrom for letter spacing as already described.

The lever 66 has an end 100 on one end of which is a roll 101, and this roll is adapted to be engaged by a bar 102. The bar 102 extends lengthwise of the carriage between the base 41 thereof and the carriage bed 43. This bar has angularly arranged slots or cam surfaces 103 which are engaged by pins 104 extending upward from the carriage bed, so that when said bar or element 102 is given a lengthwise movement, the cam slots 103 by reason of the pins 104 will cause the said bar to move laterally until its edge 104^a 129

engages the roll 101 and moves the lever 66 on its pivot 67 to release the loose dog 55 from engagement with the toothed wheel 53. The bar 102 may have a projecting end at either or both sides of the machine, as at 105, Fig. 2, for operating said bar, or said bar may be forced in one direction by a spring, if desired.

To prevent the lever 56 to which the lever 66 is pivoted from being also moved at the same time and thereby causing the fixed dog 54 to engage one of the teeth either by reason of friction or otherwise, I provide an extension 106 on one end of the lever 56 adjacent to the part 99 which is engaged by the tappet 98, and said extension 106 has a curved edge portion 107 which is concentric to the pivot 108 of a bell-crank lever 109. The bell-crank lever 109 is pivoted to an extension 110 on the member 45 of the escapement frame and said bell-crank lever has one arm 111 provided with a roll 112 which is adapted to be engaged by the edge 104 of the slideable bar 102 in a manner similar to the roll 101 and serves to move the bell-crank lever 109 on its pivot 108. The rolls 101 and 112 are held to rotate on pins which project upward through slots in the carriage base or bed in alignment with the edge 104 of the bar 102, and the roll 112 is so positioned relatively to the roll 101 that the said roll 112 on the bell-crank lever 109 will be engaged and the bell-crank moved before the lever 66 is operated through the roll 101. The purpose of moving the bell-crank lever before operating the lever 56 is to cause the said bell-crank lever to positively lock the lever 56 and hold the dog 54 out of engagement with the toothed wheel 53, and the purpose of the rolls 101 and 112 is to reduce friction during the sliding movement of the release bar 102. The arm 113 of the bell-crank lever 109 carries a screw 114, and this screw or engaging element has one end 115 which is adapted to engage the curved edge 107 of the extension 106 and lock the lever 56 against movement before the bar engages the roll 101, the said screw 114 being locked in its adjusted position by means of a lock nut 116. The bell-crank lever when the bar 101 is released is normally forced against the action of the bar by a spring 117, one end of which spring is fastened to the arm 113 of the bell-crank lever and at the other end to a pin on the bracket 110, the movement of the bell-crank lever being limited by a stop or pin 118 arranged on the bracket or extension 110. By this means, the carriage may be moved readily in either direction by positively releasing the pawls from engagement with the toothed wheel of the escapement, or the carriage may be moved quickly forward by the propelling mechanism for tabulating or for any other purpose.

It will be understood that the degree of movement of the levers may be varied and that any suitable means may be provided whereby the levers may be held in such movement to keep the dogs out of engagement with any of the teeth of the wheel, or that means may be provided if desired whereby the action of the propelling mechanism may be arrested to prevent a movement of the carriage when the dogs are thus operated.

In the construction shown and described, it is intended that the universal bar be engaged by the key-levers in the last quarter of the movement of the type-bars. The short distance of travel makes it possible to adjust the trip of the escapement within a fraction of an inch with safety, thereby practically entirely avoiding the liability of piling letters often due to a long-range trip as is present in many of the typewriting machines. The even engagement of the universal bar of each key-lever is made possible by the mechanism described and the special construction of the ear or part 92^a of each key-lever or the part 20 of each key-lever may be utilized for this purpose either or both of which can be bent very easily up or down with the proper tool from the outside of the machine after the whole machine is assembled, the part 20 serving to permit adjustment of the link 21. The construction of the key-levers is not claimed in the present application, nor is the key-lever movement as well as certain other features attempted to be covered in this application, as such features form subject matter for separate applications filed by me.

While I show and describe a universal action and other features, these are not claimed herein as they form part of other applications filed by me, the said universal bar action being covered by a divisional application filed August 24, 1914, Serial No. 858,274.

From the foregoing, it will be seen that a simple and efficient escapement mechanism is provided which may be applied to various forms of writing machines or machines in which the platen and carriage may be moved or shifted into compact relation to another part of the machine when not in use; that said parts are simple in construction and may be readily made and assembled; and that said mechanism permits a part thereof to be folded with the carriage and the other part to remain in coöperative relation with the key-levers during the folding or the shifting movement of the carriage.

Having thus described my invention, I claim as new and desire to secure by Letters Patent:

1. In a typewriting machine, the combination with a support, of a carriage adapted to move along said support, propelling

mechanism, a rack held to the carriage, a pinion engaging the rack, a ratchet wheel movable with the pinion, a lever having a fixed dog, a second lever pivoted to the first-mentioned lever, a loose dog pivoted to the second lever, means for positioning the levers and the loose dog, a plurality of key-levers, and means movable by the key-levers whereby the first-mentioned lever may be actuated 10 to disengage the loose dog in one movement and to permit the carriage to move for letter spacing on the return movement of the key-levers.

2. In a typewriting machine, the combination with a support, of a carriage adapted to move along said support, a rack held to the carriage, a pinion engaging the rack, a ratchet wheel movable with the pinion, a lever having a fixed dog, a second lever pivoted to the first-mentioned lever, a loose dog pivoted to the second lever, means for positioning the levers and the loose dog, a plurality of key-levers, and a rocking frame 20 actuated by the key-levers and adapted to move the first-mentioned lever to permit the carriage to move for letter spacing.

3. In a typewriting machine, the combination with a support, of a carriage adapted to move along said support, propelling mechanism, a rack held to the carriage, a pinion engaging the rack, a ratchet wheel movable with the pinion, a lever, a fixed dog movable with the lever, a second lever pivoted to the first-mentioned lever, a loose dog pivoted to the second lever, means for operating the levers together, and means for operating the second lever independently of the first mentioned lever.

4. In a typewriting machine, the combination with a support, of a carriage adapted to move along said support, propelling mechanism, a rack held to the carriage, a ratchet wheel, means operated by the ratchet wheel to move the rack, a lever, a fixed dog movable with the lever, a second lever pivoted to the first-mentioned lever, a loose dog pivoted to the second lever, means for positioning the levers and the loose dog, a plurality of key-levers, a rocking frame adapted to operate the first-mentioned lever, and a universal bar connected to the rocking frame and actuated by the key-levers.

5. In a typewriting machine, the combination with a support, of a carriage mounted to move along said support, propelling mechanism for the carriage, a rack held to the carriage, a pinion engaging the rack, a toothed wheel held to move with the pinion, two movable levers, one of which carries a fixed dog and the other a loose dog, and means whereby the two levers may be moved in unison or one independently of the other.

6. In a typewriting machine, the combination with a support, of a carriage mounted to move along said support, two relatively

movable levers yieldingly held together, one of which carries a fixed dog and the other a loose dog, means coöperating with the dogs to permit the carriage to move for letter spacing, and means for operating the levers. 70

7. In a typewriting machine, the combination with a support, of a carriage mounted to move along said support, propelling mechanism for the carriage, two pivotally held levers, one of which carries a fixed dog, 75 and the other a loose dog, means controlled by said levers whereby the carriage may move for letter spacing, and means whereby the two levers may be moved in unison or one independently of the other. 80

8. In a typewriting machine, the combination with a support, of a carriage adapted to move along said support, a rack mounted on the carriage, a toothed wheel operatively connected to said rack, a frame, a lever having a fixed dog pivotally held to said frame and having a part thereof engaging a part of the frame to limit its movement in one direction, a spring for forcing the lever in one direction, a second lever pivotally held to the first-mentioned lever, a stop carried by the first-mentioned lever adapted to engage a part of the second lever, a spring normally forcing the second lever in engagement with said part of the first-mentioned 95 lever, a loose dog pivotally held to the second lever, a spring normally forcing the dog in one direction, a stop carried by the second lever adapted to limit the movement of the dog in one direction, said levers having 100 means for moving the same independently, a plurality of key-levers, and means actuated by the key-levers to operate the escapement lever.

9. In a typewriting machine, the combination with a support, of a carriage adapted to move along said support, a toothed rack, a toothed wheel operatively connected to said rack, a frame, a lever having a fixed dog pivotally held to said frame, a spring for forcing the lever in one direction, a second lever pivotally held to the first-mentioned lever, a stop carried by the first-mentioned lever adapted to engage a part of the second lever, a spring normally forcing the second lever in engagement with the part of the first-mentioned lever, a loose dog pivotally held to the second lever, a spring normally forcing the dog in one direction, a stop carried by the second lever adapted to limit the movement of the dog in one direction, a plurality of key-levers, and means coöperating with the key-levers adapted to engage the first-mentioned lever to actuate the same to permit the carriage to move for letter spacing. 115

10. In a typewriting machine, the combination with a support, of a carriage adapted to move along said support, a toothed rack mounted on the carriage, a toothed wheel 120

- operatively connected to said rack, a lever, a spring for forcing the lever in one direction, a second lever pivotally held to the first-mentioned lever, a stop carried by the 5 first-mentioned lever adapted to engage a part of the second lever, a spring normally forcing the second lever into engagement with the stop of the first-mentioned lever, a loose dog pivotally held to the second lever, 10 a spring normally forcing the dog in one direction, and means for actuating the levers.
11. In a typewriting machine, the combination with a support, of a carriage adapted to move along said support, a rack mounted 15 on the carriage, a toothed wheel operatively connected to said rack, a pivoted lever having a fixed dog, a stop for the lever, a spring for forcing the lever in one direction, a second lever pivotally held to the first-mentioned lever, a stop carried by the first-mentioned lever, a stop carried by the first-mentioned lever adapted to engage a part of the second lever, a spring normally forcing the second lever into engagement with the stop of the first-mentioned lever, a loose dog pivotally held to the second lever, 25 a spring normally forcing the dog in one direction, a stop carried by the second lever adapted to limit the movement of the dog in one direction, and means for operating the levers.
- 30 12. In a typewriting machine, the combination with a support, of a carriage adapted to move along said support, a rack mounted on the carriage, a toothed wheel operatively connected to said rack, a frame, a lever having a fixed dog pivotally held to said frame, a second lever pivotally held to the first-mentioned lever, a loose dog pivotally held to the second lever, a spring normally forcing the dog in one direction, a stop carried 35 by the second lever adapted to limit the movement of the dog in one direction, said levers having means for moving the same, a plurality of key-levers, and means actuated by the key-levers to operate the escapement.
- 40 13. In a typewriting machine, the combination with a support, of a carriage mounted to move along said support, two relatively movable levers, one of which carries a fixed dog and the other a loose dog, and means for operating one lever independently of the other and for locking the lever not moved.
- 45 14. In a typewriting machine, the combination with a support, of a carriage mounted to move along said support, two relatively movable levers, one of which carries a fixed dog and the other a loose dog, and means for locking one lever against movement and subsequently operating the other lever.
- 55 15. In a typewriting machine, the combination with a support, of a carriage mounted to move along said support, an escapement mechanism including two relatively movable levers, one of which carries a fixed dog
- and the other a loose dog, means coöperating with the levers to move the carriage for letter spacing, a slidably held bar, a locking device, and means whereby said bar may operate the locking device to engage 70 one of the levers and hold the same against movement and on further movement engage and operate the other lever to move one of the dogs carried thereby.
16. In a typewriting machine, the combination with a support, of a carriage mounted to move along said support, an escapement mechanism including two relatively movable levers, one of which carries a fixed dog and the other a loose dog, a slidably held 75 bar, a locking device, and means whereby said bar may operate the locking device to engage one of the levers and hold the same against movement.
17. In a typewriting machine, the combination with a support, of a carriage mounted to move along said support, an escapement mechanism including two relatively movable levers, one of which carries a fixed dog and the other a loose dog, and a slidably held 80 bar engaging one of the levers to shift the position of the dog carried thereby.
18. In a typewriting machine, the combination with a support, of a carriage mounted to move along said support, an escapement mechanism including two dogs, and means for locking one of the dogs against movement and for moving the other dog.
19. In a typewriting machine, the combination with a support, of a carriage mounted to move along said support, an escapement mechanism including two spacing dogs, and means for locking one of the dogs against movement and for subsequently moving the other dog.
- 100 20. In a typewriting machine, the combination with a support, of a carriage mounted to move along said support, an escapement mechanism including a fixed dog and a loose dog, a slidably held bar mounted upon the support, and means coöperating with the bar and operated thereby to lock one of the dogs against movement and during the same movement of said bar cause a movement of the other dog.
- 105 21. In a typewriting machine, the combination with a support, of a carriage mounted to move along said support, an escapement mechanism including a fixed dog and a loose dog, a slidably held bar mounted upon the support, a bell-crank lever operated by the bar to hold one dog against movement, and means operated by the bar to cause a movement of the other dog.
- 110 22. In a typewriting machine, the combination with a support, of a carriage mounted to move along said support, an escapement mechanism including two relatively movable levers, one pivoted on the other, one of which carries a fixed dog and the

other a loose dog, means coöperating with the levers to move the carriage for letter spacing, a roll mounted on one of the levers, a bell-crank lever, an adjustable engaging element carried by said bell-crank lever adapted to engage the fixed dog lever, a roll held to the said bell-crank lever, a spring normally forcing the bell-crank lever in one direction, a bar slidingly held on the support and having one edge adapted to engage the rolls of the bell-crank lever and the loose dog lever in succession, and means whereby the bar may be operated to cause the engaging element of the bell-crank lever to lock one of the fixed dog levers against movement and to move the other lever.

23. In a typewriting machine, the combination with a support, of a carriage mounted to move along said support, an escapement mechanism including two relatively movable levers, one pivoted on the other, one of which carries a fixed dog and the other a loose dog, a bell-crank lever, an engaging element carried by said bell-crank lever, a spring normally forcing the bell-crank lever in one direction, a bar slidingly held on the support and having one edge adapted to engage the bell-crank lever and subsequently one of the dog-carrying levers for the purpose set forth.

24. In a typewriting machine, the combination with a support, of a carriage mounted to move along said support, an escapement mechanism including two relatively movable levers, one of which carries a fixed dog and the other a loose dog, a bell-crank lever, an adjustable engaging element carried by said bell-crank lever, a spring normally forcing the bell-crank lever in one direction, a bar having cam slots and slidingly held on the support, and pins entering the slots to impart a lateral movement to the bar when given a lengthwise movement.

25. In a typewriting machine, the combination of a support, a carriage mounted to move along said support, an escapement mechanism including a toothed element and two levers, one of which carries a loose dog, and the other a fixed dog, means for operating said levers, and means for locking one

lever with its dog released from the toothed element and subsequently moving the other lever.

26. In a typewriting machine, the combination of a support, a carriage mounted to move along said support, an escapement mechanism including a toothed element and two dog-carrying levers, and means for locking one lever with its dog released from the toothed element and subsequently moving the other lever.

27. In a typewriting machine, the combination of a support, a carriage mounted to move along said support, an escapement mechanism including two dog-carrying members, a toothed element adapted to be engaged by the dogs of the members, one of which members is mounted on the other and both adapted normally to move in unison during the letter spacing movement, one of said members being movable independently of the other to release the dog carried thereby from engagement with the toothed element, and means for operating the members.

28. In a typewriting machine, the combination of a support, a carriage mounted to move along said support, an escapement mechanism including two pivotally held levers each carrying a dog, one of said levers being pivotally mounted on the other and both levers adapted normally to move in unison during letter spacing and one of said levers being movable independent of the other, and means for operating the levers.

29. In a typewriting machine, the combination of a support, a carriage mounted to move along said support, an escapement mechanism including two levers one pivotally mounted on the other, one of which levers carries a loose dog and the other a fixed dog, and means for operating said levers.

This specification signed and witnessed 9
this 11th day of April A. D. 1911.

OTTO PETERMANN.
